UNITED STATES PATENT OFFICE.

DANA E. HARDING, OF DANVERS, MASSACHUSETTS, ASSIGNOR TO HARDING ENGINEERING COMPANY, OF EAST BOSTON, MASSACHUSETTS, A CORPORATION OF MASSACHUSETTS.

COATING MACHINE.

Application filed April 11, 1922. Serial No. 551,732.

To all whom it may concern:

Be it known that I, DANA E. HARDING, a citizen of the United States, residing at Danvers, in the county of Essex and State of 5 Massachusetts, have invented new and useful Improvements in Coating Machines, of which the following is a specification.

The present invention relates to applying liquid to traveling surfaces. It is applicable 10 to many specific uses, including that of spreading dye or pigment on skins and leather, painting cloth, boards, and any other articles capable of being transported under a delivering tank or being so held that a painting machine may be passed over it, and in 15 general for any use where it is desired to spread a liquid evenly over a wide surface.

The particular object of the invention is to provide means for delivering the dye, 20 pigment, paint or other coating liquid from a tank, regulating its rate of flow, and distributing the liquid evenly over the whole extent of the surface to be coated. These objects are accomplished by the means which 25 form the subject of the present invention and are described in the following specification in connection with a practical construction of coating machine illustrated in the accompanying drawings.

30 While my present invention is of general use as above noted, it is of particular value in seasoning leather for various purposes, such for example as applying color to hides, skins, leather or the like, supplying a coating for finishing, or preparatory for glazing, or for softening and treating and to 35 this end the apparatus herein shown may be utilized in connection with an enclosing oven or other heat retaining apparatus. The control of the opening for the flow of liquid to the applying brush regulating the supply is 40 an important feature, this being capable of use during the operation of the machine, and without stopping the apparatus.

45 Referring to the drawings,—

Figure 1 is an elevation of a coating machine in connection with which the invention is used.

Figure 2 is an enlarged sectional view of 50 the liquid delivering and spreading means.

Figure 3 is a sectional view of the regulating supply valve.

Like reference characters designate the 55 same parts in all the figures wherever they occur.

In Figure 1 *a* represents a frame which supports a roll *b* over which a conveyer *c* passes. The conveyer also passes around another roll (not shown) by which it is held in a sufficiently stretched condition, and by 60 one or both of which it is propelled. *d* represents a standard rising from the frame which supports a tank or trough *e* containing the dye, solution of pigment, paint or other coating material.

Referring now particularly to Figures 2 and 3, the tank *e* is equipped at its lowest point with a valve chamber *f* having a large number of ducts or passages *g* arranged side by side and opening through the bottom of the tank at one end and from the valve chamber at the other end. The tank and the valve casing have a length preferably as great as the width of the conveyer *c* and at least as great as the width of the articles to be coated, or of the portions of such articles to which the coating is to be applied. The ducts are spaced equally or approximately so throughout the length of the valve, in order to effect a distribution of the liquid 70 delivered.

A valve body or cock *h* occupies a chamber in the valve casing and crosses the ducts *g*. This valve and the chamber which it occupies are preferably complementally cylindrical, so that the valve body may be rotated. It is within my contemplation, however, that the valve be mounted non-rotatably, and that it may be moved endwise so as to open or close the ducts wholly or in part. In the latter case it need not be cylindrical; however as illustrated the valve is designed for rotation, and it is held against endwise movement by a collar *i* at one end and a plug *j* at the other end. It carries a handle *k* by 80 which it may be turned.

In the valve body are passages *l* spaced equally with the passages *g* of the valve casing and adapted to be placed in register or out of register with the latter passages to 100 a greater or less extent by the described movement of the valve. Instead of these passages *l* being made as transverse holes through the valve body, they may be made as slots cut part way through the valve from one side, or the whole side of the valve may be cut away continuously throughout so much of its length as lies in the region of the passages *g*. However the valve may be made in detail, in principle it is so con- 105 110

structed that it may open or close all of the outlet passages from the tank either wholly or in part, and so open or close all of them equally at the same time.

- 5 To the side of the valve casing *f* is secured a brush head or holder *m* which carries bristles *o* so closely distributed throughout its length and otherwise so disposed that their ends bear on the conveyer and 10 upon whatever flat articles may be carried by the conveyer. This brush crosses the outlets of the several passages *g*, whereby the discharge of liquid from these passages occurs first on the brush and the liquid does 15 not reach the article being coated until it has flowed over and between the brush bristles. In thus flowing over the bristles, the liquid is thoroughly distributed and when it passes from the end of the latter 20 to the traveling surface beneath, it is uniformly distributed over that surface.

Other elements of the machine include a roll *p* arranged directly under that part of the conveyer which lies under the brush and 25 other rolls *q* and *r* arranged over the conveyer adjacent to the brush. The roll *p* supports the conveyer and holds its upper surface at an invariable distance from the supply tank, while the rolls *q* and *r* serve 30 to flatten out the articles being coated, in case they are of flexible material and liable to wrinkle like leather or cloth, and hold them smooth while being coated.

It will be understood that anything laid 35 on the conveyer and being not too thick to pass under the rolls *q* and *r* and the brush *o* will be carried by the conveyer under and in contact with the brush and from the latter will receive an equally distributed coating 40 of the liquid. The rate of flow of the liquid, of course, is regulated by adjustment

of the valve *h* in accordance with the viscosity of the liquid and the rate of travel of the conveyer, so that a sufficient amount of liquid will be delivered to coat the traveling surface uniformly and without excess. 45

What I claim and desire to secure by Letters Patent is:

1. A liquid supplying means for coating apparatus comprising a tank having a series of discharge outlets, valve means controlling said outlets in unison, and a brush arranged to receive the material delivered from said outlets and to distribute such material over the surface being coated, in combination with work supporting means substantially in alignment with said brush. 50

2. A liquid coating apparatus, comprising a source of liquid supply, an applying brush of substantial width, a plurality of conduits from the supply to the face of said brush, in combination with a valve having a corresponding number of conduits therethrough to register with and control the passage of liquid from the supply to the brush, and 55 means to actuate said valve.

3. A liquid supplying means for coating apparatus having, in combination, a tank, a series of discharge elements arranged parallel to each other and lying in substantially the same plane, a valve controlling said discharge outlets simultaneously, a brush associated with the discharge outlets and adapted to receive liquid therefrom at a plurality of points within the interior of the 70 brush, and work supporting and feeding means normally in engagement with the brush and movable transversely thereof. 75

In testimony whereof I have affixed my signature.

DANA E. HARDING.
